LADY'S HAND LUGGAGE

George Henry Wheary, Racine, Wis., assignor to
 The Wheary Trunk Company, Racine, Wis., a
 company of Wisconsin

Application January 28, 1931, Serial No. 511,703

5 Claims. (Cl. 190—41)

This invention relates to certain new and useful improvements in lady's hand luggage, and has as an object to provide a lady's hand case in which garments, and particularly dresses, of any length may be carried without wrinkling and without necessitating the alteration in any respect of the over-all size of the case.

A more specific object of this invention resides in the provision of an improved case having a garment carrying frame similar to that illustrated in the copending application of George Henry Wheary and Benjamin M. Hamlin, Serial No. 357,088, filed April 22, 1929, Patent No. 1,799,877 and provided with an intermediate transverse member or rod located at a point medially of the ends of the frame, and over which garments may be draped to extend over the outer end of the frame with the ends extended into a well in the case, to thus accommodate dresses of a length greater than twice the distance from the outer end of the garment carrying frame to the bottom of the well when the frame is in a substantially vertical position.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompany drawings, I have illustrated one complete example of the physical embodiment of my invention constructed according to the best mode I have so far devised for the practical application of the principles thereof, and in which:

Figure 1 is a perspective view of a lady's hand case or luggage embodying my invention, said view illustrating the case in open position;

Figure 2 is a fragmentary perspective view of a portion of one side arm of the garment carrying frame illustrating the attaching means for the intermediate rod members;

Figure 3 is a perspective view of one end of an intermediate rod member; and

Figure 4 is a transverse sectional view taken through Figure 1 on the plane of the line 4—4.

Referring now more particularly to the accompanying drawings, in which like numerals designate like parts, the numeral 5 represents the main section of a luggage carrier of the case type having a cover 6 hingedly connected there-

is provided with the conventional handle 8 and locking means 9.

The main section of the case preferably has a partition 10 which is removably mounted therein parallel with its rear wall or panel 11, but spaced therefrom to provide a well 12 for the reception of the depending ends of garments 13 within the case.

The garments 13 are conveniently supported on a garment carrying frame 14 consisting of a substantially U shaped member comprising side arms 15 connected at their outer ends by a transverse bar or rod 16 and having their inner end portions 17 directed inwardly and upwardly at an angle with respect to the plane of the frame proper, when in a horizontal position over the main section. The end portions 17 of the garment carrying frame are pivotally connected, as at 18, with attaching members 19, the upper ends 20, of which are likewise angularly directed. The lower ends of the attaching members are removably secured to the side walls of the main section, and in this manner the garment carrying frame is pivotally mounted and may be swung to a position as illustrated in Figure 4, for the purposes of packing and to a position over the main section as depicted in dotted lines in Figure 4, in which position the garment carrying frame and the garments thereon form an internal cover for the case.

In the copending application above referred to, the garments are draped, at a medial point, over the end member 16 of the garment carrying frame with their ends at opposite sides of the frame to extend into the well 12. A number of garments may be similarly carried on the frame, one being placed above the other, and while this method of packing is satisfactory, where the total length of the garments is not greater than twice the distance from the transverse member 16 to the bottom of the well 12 when the frame is in a vertical position, the exceptionally long dresses decreed by modern fashion cannot be accommodated in this manner without increasing the dimensions of the case or crumpling the ends of the garments.

This invention therefore contemplates the provision of simple but effective means whereby longer garments may be readily accommodated without in any wise changing the size of the case or the garment carrying frame and without wrinkling. To this end, one or more pairs of aligned keeper members 21 are secured to the side members 15 of the garment carrying frame, the keeper members projecting rearwardly from

the side members, when the garment carrying frame is in a vertical position, and having approximately J shaped slots or openings 22 therein for the reception of trunnions 23 on the ends 5 of transverse garment carrying rods 24.

One or more garment carrying rods may be provided and in the present instance, three pairs of keeper members and three transverse rods 24, are shown. As will be apparent from the description to follow, the nearer the transverse rod member 24 is to the pivotal mounting of the garment carrying frame, the greater will be the length of garment it is possible to accommodate, thus by providing rods at various intermediate 15 points, the available space may be utilized to the best advantage.

In use, the garment is medially folded over a rod 24 to divide its length substantially in two and then draped over the end member 16 20 of the garment carrying frame with the rod member 24 engaged at its ends with one pair of keepers in the manner illustrated. Transverse bars 25, but one being shown, are provided to support the garments as the frame is swung to 25 its horizontal position over the main section.

From the foregoing description taken in connection with the accompanying drawings, it will be readily apparent to those skilled in the art to which an invention of this character appertains that I provide a novel and practical means for accommodating dresses of extreme lengths without in any wise necessitating an increase in the size of the case and its appurtenances, as the effective hanging length, which heretofore extended only from the outer bar 16 of the garment supporting frame to the bottom of the well, is increased by the distance from the bar 16 to the rod or rods 24.

What I claim as my invention is:

40 1. In a case type luggage carrier including a main section member and a cover section member hingedly connected along one marginal edge, a substantially U shaped garment carrying frame comprising side arms of a length to extend from the hinged connection of the sections to the opposite walls thereof and an outer transverse bar connecting the side arms and over which garments may be draped, means hingedly mounting the garment carrying frame at the 45 free ends of its side arms in one of said section members for movement about an axis substantially parallel with that of the hinge connection between the section members, whereby said frame is movable into alignment with either section when the case is open and to a position over the main section, an intermediate transverse bar readily removably mounted on the garment carrying frame side arms at a medial point and about which garments may be folded 50 prior to being draped over the outer transverse bar of said garment carrying frame so that garments draped over said bars hang on opposite sides of the frame with their ends extending into the main section member, and means for maintaining the garments substantially in the plane of the garment carrying frame when said frame is in a position over the main section member.

55 2. A garment carrying case having hingedly connected main section and cover members, a garment carrying frame substantially co-extensive with the open sides of the hingedly connected members and including side members and an end transverse bar connecting the outer end portions of the side members and over which garments may be draped to hang on opposite

sides of the frame, said side members and outer transverse bar lying in substantially a common plane, means adjacent the hinged connection between said member for movably mounting the garment carrying frame for movement to and from an approximately right angular position with respect to the main section member and an approximately horizontal position over the main section member, and a transverse member readily detachably mounted on the side members of the garment carrying frame at a medial point and about which garments are adapted to be folded prior to being draped over the frame outer bar. 80

3. In a case type luggage including a main section having a cover hingedly connected to one marginal edge thereof, a garment carrying frame substantially co-extensive with the open sides of the main section and cover and comprising side arms having their outer ends connected by a transverse member over which garments may be draped, said side arms and transverse member lying in substantially a common plane, means pivotally connected with the inner ends of the side arms and mounting the garment carrying frame for swinging movement about an axis adjacent to and substantially parallel with the axis of the hinged connection of the main section and cover, keeper members carried by the side arms at points spaced from the transverse member connecting their outer ends, and a transverse bar adapted to have garments draped thereover and readily detachably connected with said keeper members, said transverse bar lying substantially in the plane of the frame 100 so that garments folded thereover and draped over the transverse member connecting the outer ends of the side arms will extend along one side of the frame and hang down into the main section. 90

4. In a case type luggage including a main section having a cover hingedly connected to one marginal edge thereof, a substantially U shaped garment carrying frame comprising side arms of a length substantially equal to the distance from the hinged connection of the main section and cover to the opposite walls thereof and having their outer ends connected by a transverse member over which garments may be draped, means pivotally connected with the inner ends of the side arms and mounting the garment carrying frame for swinging movement about an axis adjacent to and substantially parallel with the axis of the hinged connection of the section and cover, a plurality of keeper members carried by each side arm in spaced relation to each other and to the transverse member connecting the outer ends of the side arms, transverse garment receiving bars, and means at the outer ends of said bars for readily detachably connecting the bars with the keeper members, said bars lying in substantially the plane of the frame so that garments draped thereover extend outwardly along one side of the frame to be draped over the transverse member at the outer end thereof and then extend along the other side of the frame and into the main section. 105 110 115

5. In a case type luggage carrier comprising a main section having a cover hingedly connected thereto, a substantially U shaped garment carrying frame comprising side arms of a length substantially equal to the distance from the hinged connection of the main section and cover to the opposite walls thereof and a transverse bar connecting the outer ends of the side arms, 120 125 130 135 140 145 150

said side arms and transverse bar lying in substantially a common plane, means connected with the inner ends of the side arms for hingedly mounting the frame for swinging movement about an axis adjacent and parallel to the hinged connection of the main section and cover, said axis about which the frame swings being so located that the frame in its normal position occupies the plane of the open top of the main section, a keeper member carried by each side arm at a point intermediate the transverse bar connecting the outer ends of the side arms and the hinged mounting of the frame, and a transverse

garment supporting member having means at its opposite end portions for detachable connection with the keeper members so as to mount the transverse garment carrying member from the frame substantially parallel with the transverse bar and substantially in the plane of the frame, said transverse garment supporting member being adapted to have garments folded thereover at their medial portions with their ends extending outwardly over the transverse bar and then inwardly in the plane of the frame toward its hinged mounting.

GEORGE HENRY WHEARY.
